UNITED STATES PATENT OFFICE.

JOSIAH AMISSON, OF LAMBERTVILLE, NEW JERSEY.

DESIGN FOR A WATER-CLOSET BOWL.

42,722.

Specification for Design.

Patented July 9, 1912.

Application filed March 28, 1912. Serial No. 686,951. Term of patent 7 years.

To all whom it may concern:

Be it known that I, JOSIAH AMISSON, a citizen of the United States, and a resident of Lambertville, in the county of Hunterdon and State of New Jersey, have invented a new, original, and ornamental Design for a Water-Closet Bowl, of which the following is a specification, reference being had to the accompanying drawing, forming a part thereof.

Figure 1 is a side elevation of a water closet bowl showing my design; and Fig. 2 is a rear end view of the same.

I claim:

The ornamental design for a water closet bowl as shown.

JOSIAH AMISSON.
